US00D940156S

(12) **United States Design Patent** (10) **Patent No.:** **US D940,156 S**
Butcher et al. (45) **Date of Patent:** **** Jan. 4, 2022**

(54) **DISPLAY SCREEN OR PORTION THEREOF WITH GRAPHICAL USER INTERFACE**

(71) Applicant: **Apple Inc.**, Cupertino, CA (US)

(72) Inventors: **Gary Butcher**, San Jose, CA (US);
Alan C. Dye, San Francisco, CA (US);
Chance Graham, Campbell, CA (US)

(73) Assignee: **Apple Inc.**, Cupertino, CA (US)

(**) Term: **15 Years**

(21) Appl. No.: **29/744,278**

(22) Filed: **Jul. 28, 2020**

Related U.S. Application Data

(63) Continuation of application No. 29/674,610, filed on Dec. 21, 2018, now Pat. No. Des. 892,823, which is a continuation of application No. 29/633,339, filed on Jan. 12, 2018, now Pat. No. Des. 836,651, which is a continuation of application No. 29/607,250, filed on Jun. 12, 2017, now Pat. No. Des. 808,402, which is a continuation of application No. 29/572,565, filed on Jul. 28, 2016, now Pat. No. Des. 789,385, which is a continuation of application No. 29/501,334, filed on Sep. 3, 2014, now Pat. No. Des. 762,660.

(57)

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
